Attorney*

UNITED STATES PATENT OFFICE.

GARRETT WHITE, OF CHAPEL HILL, TENNESSEE.

THERMOSTATIC CIRCUIT CLOSER AND BREAKER.

Application filed January 10, 1925. Serial No. 1,656.

To all whom it may concern:

Be it known that I, GARRETT WHITE, a citizen of the United States, residing at Chapel Hill, in the county of Marshall and State of Tennessee, have invented certain new and useful Improvements in Thermostatic Circuit Closers and Breakers, of which the following is a specification.

The present invention appertains to a thermostatically controlled circuit maker and breaker, and has for its principal object to provide a device of this nature, with an extremely simple and efficient structure, one which is reliable in operation, inexpensive to manufacture, strong, durable, compact, easy to handle, not liable to readily get out of order, and otherwise well adapted to the purpose for which it is designed.

With the above and numerous other objects in view, as will appear as the description proceeds, the invention resides in such novel features of construction, and in the combination and arrangement of parts as will be hereinafter more fully described and claimed.

In the drawing:

Figure 1 is an elevation of the device embodying the features of my invention, and

Figure 2 is a vertical longitudinal section therethrough.

Referring to the drawing in detail, wherein in similar reference characters refer to like parts throughout the several views, it will be seen that 1 designates a panel, which is adapted to be located in a convenient position, for supporting my device. This panel is constructed of insulating material, such as porcelain or the like, and at the bottom end thereof, a binding post 2 is mounted, supported by means of screw 3. A similar binding post 4 is mounted at the top thereof, supported by another screw 3. These binding posts 2 and 4 are provided with the usual binding screws 5. A bracket indicated generally by the letter B is attached to the panel 1 by means of a bolt 6 and the lower screw 3. This bracket B includes a plate 7, having spring fingers 8 at its top and spring fingers 9 at its bottom, for grasping a metal tube 10. The bottom portion of this tube is filled with suitable material, such as plaster Paris, bakelite or the like, indicated at 11, which will tend to absorb moisture from the mercury. Insulating material 13 is positioned in the tube 10,

at its upper end, leaving a space between it and the other material 11, so as to form a compartment 14. The material 13 is provided with a vertically extending opening 15, flared at its upper end. A funnel shaped member 16' is positioned in the flared end of the opening 15, extending a slight distance above the upper end of the tube 10 and the material 13. An L-shaped bracket 17 is mounted on the upper screw 3, being in electrical contact with the binding post 4. A screw 18 is threaded through the bracket 17, so that its head may be adjusted, in relation to the funnel shaped member 16'. In making the device, a desired amount of mercury is placed in the compartment 14, and a rubber cap or the like 20, is disposed on the funnel shaped member 16', as is shown in Figure 1, for preventing spilling of the mercury, as the tube 10 is being put in place in the bracket B and being packed, shipped, etc. Suitable wires of a circuit are, of course, attached to the binding posts 2 and 4, and the circuit will be closed or opened, depending upon the temperature of the place at which this device is located.

By way of example, it will be noted that a predetermined amount of mercury has been inserted in the compartment 14, the cap 20 having been removed and screw 18 engaged with member 16', that as the temperature rises, the mercury will rise into the opening 15 and into the funnel 16'.

When this device is to be used as a circuit closer for giving an alarm, it will be noted that the mercury in the compartment 14 will rise in the column 15 and the circuit will be closed, as soon as this mercury touches the lower end of the funnel shaped contact member 16'. The circuit will be closed through the binding post 2, tube 10, the mercury, the funnel shaped member 16', the screw 18, the bracket 17, and the binding post 4. When the device is to be used as a circuit breaker for giving an alarm, the mercury is in contact with the funnel shaped contact member 16', and when the temperature lowers, the column of mercury will lower and recede from engagement with the contact 16'. This, of course, breaks the circuit. The proper amount of mercury is installed in the compartment 14, during the manufacture of the device, depending upon the purpose for which it is to be used. Be-

fore the device is placed in use, it is well to jar the same, in order to insure the proper location of the mercury, and then the rubber cap 20 is removed, and the screw 18 engaged directly with the funnel shaped contact member 16' as illustrated in Figure 2. The funnel shaped contact member 16' accommodates the mercury as it rises above the lower end thereof. It will be apparent that the device may be used in the operation of a large number of different alarm devices, for a large number of different purposes.

It will be apparent from the above that the device is very simple, yet efficient, and that there is nothing which is liable to readily get out of order. Although I have described the invention with a certain degree of particularity, it is to be understood that numerous changes in the details of construction, in the materials, and in the combination and arrangement of parts may be resorted to, without departing from the spirit or scope of the invention, as hereinafter claimed, or sacrificing any of its advantages.

Having thus described my invention, what is claimed as new is:

In a device of the class described, a panel of insulating material, a bracket on the panel provided with spring fingers, a binding post securing the lower end of the bracket to the panel, a tube engageable by the spring fingers and having its lower end resting on the binding post, insulating material closing the bottom of the tube, insulating material in the top of the tube spaced from the first-mentioned material to form a compartment, said second mentioned insulating material provided with a restricted passage leading from the compartment and terminating at its upper end in a funnel-shaped recess, a funnel of electricity conducting material seated in the recess and projecting slightly above the upper end of the tube, a separate binding post on the panel above the upper end of the tube, a bracket depending from the second binding post, a screw in the second bracket and adjustable toward and away from the funnel.

In testimony whereof I affix my signature.

GARRETT WHITE.
